SURFACE UNIT ASSEMBLY
Joseph J. Jasionowski, Niles, Ill., assignor to Ferro
Corporation, a corporation of Ohio
Filed May 13, 1964, Ser. No. 367,161
1 Claim. (Cl. 219—447)

This invention relates to electrical surface units for use in electric ranges and more particularly to an electric surface unit assembly which is particularly adaptable for use as a substitute unit for gas burners in a stove utilizing the major components of a gas range.

It is the general object of the present invention to produce a new and improved surface unit and surface unit assembly of the character described.

The use of electricity in cooking is constantly increasing and many manufacturers of gas stoves have recognized this fact and sought to expand their scope of operations to include the manufacture not only of gas stoves but also of electric stoves. In such instances, the manufacturer desires to use as many of the components and as much of the design of the gas stove as he can while making the conversion to an electric stove. The electrical surface unit assembly of the present invention is particularly adapted to act as a substitute for gas burners utilizing a great number of the components of a gas stove and without requiring any substantial changes in design. Accordingly, it is a further object of the present invention to produce an electrical surface unit assembly which can be utilized by the manufacturer of a gas stove as a substitute for gas burners in such stoves, with but a minimum of redesign being necessary to effect the changeover.

Other and further objects and advantages of the present invention will be readily apparent from the following description and drawings, in which:

FIG. 1 is a top plan view of a gas stove incorporating the unit of the present invention;

FIG. 2 is an exploded view showing the upper portion of the gas stove of FIG. 1 and the unit usable therewith;

FIG. 3 is a top plan view of a lower left-hand portion of FIG. 1 and somewhat enlarged;

FIG. 4 is a vertical sectional view along line 4—4 of FIG. 3;

FIG. 5 is a sectional view of the terminal portion of a two coil unit showing the mounting plate;

FIG. 6 is a sectional view along line 6—6 of FIG. 5.

While this invention is susceptible of embodiment in many different forms, there is shown in the drawings and will herein be described in detail a specific embodiment, with the understanding that the present disclosure is to be considered as an exemplification of the principles of the invention and is not intended to limit the invention to the embodiment illustrated. The scope of the invention will be pointed out in the appended claims.

Referring now to the drawings, there is shown a gas stove top 10 provided with the usual burner rough box 11 fitted on the top of the stove. A cook top 12 overlies the burner rough box and is secured thereto by the screws 13 as shown in FIG. 4. Resting on the cook top is a grate 14 having a plurality of openings 15 therein, each receiving a heating coil 16. The heating coils are shown as being provided with a sensor unit although it may also be desirable to utilize fewer sensors or none at all. The coils are each supported in the grate opening and on the upper surface of the cook top by means of three-legged spiders 17, each leg of which is provided with a depending portion 18 resting on the upper surface of the cook top and supporting the coil 16 in such position. Terminals

2

20 extend vertically downwardly from the surface unit and through a mounting plate 21 provided with apertures through which the terminals extend. The coil 16 may have two or four terminals, depending upon the nature of the surface unit itself, the coil shown in FIG. 3 being provided with two such terminals while four terminals are shown in FIGS. 5 and 6.

The mounting plate 21 is constructed to rest upon and be secured to the upper surface of the cook top by means of screws 22, there being a silicone rubber gasket positioned to be compressed between the mounting plate 21 and the upper surface of the cook top 12 so as to provide a tight seal therebetween. The terminals 20 extend through a slot 24 in the cook top positioned beneath each of the openings 15 in the grate and terminate in insulating connector blocks 25 located in the space existing between the burner rough box 11 and the underside of the cook top 12. The blocks 25 are, of course, connected to suitable sources of electrical energy to provide current for the heating coils. If desired, a pan control 26 of usual construction may be used, the control having a terminal 27 extending through the mounting plate 21 as indicated.

The mounting plate is of course sealed to the essential surfaces of the terminals 20 as they pass therethrough preferably by crimping the edges of the apertures against the terminals and the unit thus provides a liquid-tight arrangement which may be cleaned by the housewife simply by removing the grate and thereby exposing the cook top surface. Any leakage of fluids is prevented by the seals described from entering into the space beneath the cook top.

It will be noted that the only change of consequence in design from the usual gas stove is simply the elimination of the gas burner, and the surface unit of the present invention can readily be slipped in place over the burner rough box of the conventional gas stove. The energy being electrical, it will require of course suitable electrical conduits, switches, etc. for operation, but these may be of conventional form and present no problem.

I claim:

A surface unit assembly particularly adaptable for use as a substitute for gas burners in a gas cook stove having a burner rough box comprising, a cook top shaped to overlie the rough box, a grate supported over the bottom of the cook top and having a plurality of openings therein, an electrical heating coil in each opening, a three-legged spider having downwardly extending leg portions resting on the upper surface of the cook top for supporting each coil in a horizontal position in its respective opening, each coil having electric terminals extending vertically downwardly from the coil, a mounting plate having apertures through which the terminals of each coil extend, the edges of the apertures sealingly engaging the terminals, a gasket, means securing the mounting plate to the cook top and compressing the gasket between the bottom of each mounting plate and the upper surface of the cook top to seal the juncture therebetween, and means in the space between the cook top and the burner rough box for supplying electrical energy to said terminals.
